UNITED STATES PATENT OFFICE.

CARL E. BROWN, OF COLUMBUS, OHIO.

DESIGN FOR A ZITHER-BODY.

SPECIFICATION forming part of Design No. 36,015, dated August 19, 1902.

Application filed June 13, 1902. Serial No. 111,588. Term of patent 14 years.

To all whom it may concern:

Be it known that I, CARL E. BROWN, a citizen of the United States, residing at Columbus, in the county of Franklin and State of Ohio, have invented a new, original, and ornamental Design for Zither-Bodies, of which the following is a specification, reference being had to the accompanying drawings, forming part thereof.

10 In the drawings referred to, Figure 1 shows a face view of my newly-designed zither-body, and Fig. 2 is a side elevation of the same.

As shown in the drawings, the leading or material feature of my design consists in the 15 approximately oval lower portion 1, from the upper side of which rise opposing scroll-like arms 2, these arms being formed with outwardly and downwardly curved upper end portions and with curved outer side recesses

at their bases, said arms, connected in their 20 upper portions by an intervening bar 3, having rounded upward projections, and the lower or body portion 1 having a flaring base 4. The center of the body is formed with a circular opening, (indicated at 5.) 25

Having described my invention, what I claim as new, and desire to secure by Letters Patent, is—

The ornamental design for a zither-body as herein shown and described. 30

In testimony whereof I have signed my name to this specification in the presence of two subscribing witnesses.

CARL E. BROWN.

Witnesses:

C. C. SHEPHERD,
A. L. PHELPS.
